UNITED STATES PATENT OFFICE.

JOSEPH B. AUERBACH, OF NEW YORK, N. Y., ASSIGNOR TO JOSEPH S. ARVID CO., OF NEW YORK, N. Y., A CORPORATION OF NEW YORK.

DESIGN FOR A DISPLAY SIGN.

Application filed February 27, 1928. Serial No. 25,605. Term of patent 14 years.

To all whom it may concern:

Be it known that I, JOSEPH B. AUERBACH, a citizen of the United States, residing at the city of New York, in the county of New York and State of New York, have invented a new, original, and ornamental Design for a Display Sign, of which the following is a specification, reference being had to the accompanying drawing, forming part thereof.

The figure is a perspective view of a display sign, showing my new design.

I claim:

The ornamental design for a display sign, substantially as shown.

JOSEPH B. AUERBACH.
